UNITED STATES PATENT OFFICE.

EDWARD L. CONRAD, OF KANSAS CITY, MISSOURI.

WRENCH.

Application filed February 28, 1925, Serial No. 12,435. Renewed August 22, 1927.

This invention relates to new and useful improvements in wrenches, and particularly to pipe wrenches.

One object of the invention is to provide a wrench wherein the pivoted jaw is so arranged, with respect to the fixed jaw, that the greatest leverage may be obtained when the wrench is in operation.

Another object is to provide means operable between the jaws of the wrench, whereby the wrench is adapted for use with differently sized pipes or rods, without the usual necessity of adjusting the pivot of the pivoted jaw.

Another object is to provide a means, operable between the fixed and movable jaws, which is arranged for longitudinal adjustment, with respect to the fixed jaw, in such manner as to regulate the space between the jaws, and provide for efficient gripping action on a rod or pipe, before the said means and the movable jaw become parallel with each other.

Another object is to provide a jaw face, or insert, arranged to interlock with the fixed jaw, and which is adjustable into different longitudinal positions on the fixed jaw, as well as being readily withdrawn from the fixed jaw, to permit the fixed jaw to cooperate with the pivoted jaw.

Other objects and advantages will be apparent from the following description when taken in connection with the accompanying drawing.

In the drawing:

Figure 1 is an elevation of a wrench made in accordance with the present invention, and with the insert engaged with the fixed jaw.

Figure 2 is a side elevation of the wrench showing the insert withdrawn from the fixed jaw.

Figure 3 is a top plan view of the wrench with the pivoted jaw broken away.

Figure 4 is an enlarged vertical longitudinal sectional view on the line 4-4 of Figure 3.

Referring particularly to the accompanying drawing, 10 represents the shank of the wrench on one end of which is formed the enlarged portion 11, forming the fixed jaw.

The upper face of this enlarged portion 11 is downwardly and longitudinally inclined, and formed with a plurality of transverse ratchet teeth 12. The upper portion of the inclined face of the fixed jaw 11 is un-

toothed, as shown at 13. Straddling this portion 11, and pivotally connected thereto, are the legs 14 of the pivoted jaw 15, said jaw having the toothed face 16 for cooperation with the fixed jaw, and with an insert which will presently be explained.

On the upper edge face of the shank 10, and at a suitable distance from the fixed jaw, there is secured the boss 17, and formed longitudinally through this boss is an opening 18, which slidably receives the rod 19. On the forward end of the rod 19 there is fixed a block 20, the side faces of which are scored, as shown at 21, and the forward end 70 of which is bifurcated, at 22, to receive the reduced and apertured rearward extension 23, of the insert block 24. Within the bifurcated portion of the block 20, and bearing against the block and the said extension 75 23, is a coil spring 25. The side faces of the insert block 24 are parallel, but the upper and lower faces 26 and 27 converge in the direction of the outer or forward end of the block. Both of these faces 26 and 27 are formed with transverse ratchet teeth 28. The upper face of the rod 19, rearwardly of the block 20, and for a certain distance from said block, is formed with teeth or scores 29, for engagement by the 80 thumb of the hand which holds the shank of the wrench, and by means of which the rod may be slipped forwardly and rearwardly, to place and withdraw the insert block 24. A stop pin 30 is secured in the side 85 of the rod 19, rearwardly of the boss 17, for engagement with said boss to limit the forward sliding movement of the rod, whereby to properly position the insert block 24 on the face of the fixed jaw. It will be noted 90 that the blocks 20 and 24 slide on the upper edge face of the shank, between the legs of the pivoted jaw.

As the rod 19 is pushed forwardly, the blocks 20 and 24 move between the legs of the pivoted jaw 15, and the spring 25 urges the insert block toward the upper edge face of the shank, with the result that when the insert block is disposed over the toothed face of the fixed jaw, said insert will be forced 100 down so that its lower toothed face engages with the toothed face of the fixed jaw. The pin 30 prevents any further forward movement of the insert block, while the interlocking engagement of the teeth of the block, with the teeth of the fixed jaw, prevent any 105 rearward movement of the insert block, the 110

spring 25 maintaining these teeth in engagement.

To withdraw the insert from the fixed jaw, it is only necessary to press the rod 19 inwardly toward the edge face of the shank. Thus movement causes the block 20 to move inwardly, and the pivoted end of the insert block to be rocked on its rear end, as a fulcrum, which rear end rests on the 10 untoothed portion of the fixed jaw. This disengages the teeth of the insert block from the teeth of the fixed, when the rod, and blocks, may be readily slipped rearwardly, thus removing the insert block from interference with the cooperative action of the fixed jaw and the pivoted jaw, for operation upon a piece of work of different diameter.

On one side face of the enlarged portion 11, of the shank, there is disposed an outwardly extending pin 31, which is arranged to be engaged by a pin which projects from the lower edge face of the adjacent leg of the pivoted jaw, shown at 32, for limiting the forward swinging movement of the said 25 jaw, and thereby properly position the jaw with relation to the fixed jaw.

What is claimed is:

1. A wrench including a fixed toothed jaw and a movable jaw, a toothed insert movable 30 into and out of interlocking engagement with and position on the fixed jaw, a rod movably connected with the insert and slidably supported in position for moving the insert toward and away from the fixed 35 jaw, and means for urging the insert into interlocking engagement with the fixed jaw.

2. A wrench including a fixed toothed jaw and a movable jaw, a toothed insert movable into and out of interlocking engagement 40 with the fixed jaw, the fixed jaw having a shank, a block slidable on the shank and movably connected with the insert, a stem connected with the block slidably supported on the shank and means between 45 the block and the insert for rocking the latter into interlocking engagement with the fixed jaw.

3. A wrench including a shank having a fixed toothed jaw, a movable jaw mounted 50 thereon, a toothed insert movable on the shank into and out of interlocking engagement with the fixed jaw, a block slidable on the shank and pivotally connected with the insert for movement thereof, a stem carried 55 by the block, guiding means for the stem on the shank, and resilient means between the block and the insert for rocking the lat-

ter into interlocking engagement with the fixed jaw.

4. A wrench including a shank having a 60 fixed toothed jaw, a movable jaw mounted thereon, a tapered and toothed insert slideable on the shank into and out of interlocking engagement on the fixed jaw, a block 65 slidable on the shank and pivotally connected with the insert, a rod carried by the block and guided on the shank, stop means on the rod for engagement with the shank, and resilient means between the insert and block for normally urging the insert toward the 70 fixed jaw.

5. A wrench including a shank having a 75 fixed jaw on one end and provided with teeth, a jaw pivotally supported on the fixed jaw and movable toward and away therefrom, a guide on the shank, a rod slideable through the guide, a block on one end of the rod, a block movably connected with the first block and having teeth for interlocking engagement with the teeth of the fixed 80 jaw and teeth for cooperative working action with the pivoted jaw, and means for urging the second block into interlocking engagement with the fixed jaw.

6. A wrench including a shank having a 85 fixed toothed jaw, a jaw pivotally supported on the fixed jaw and movable toward and away therefrom, a tapered insert movable into and out of position on the fixed jaw and having teeth for interlocking engagement 90 with the teeth of the fixed jaw and teeth for cooperative action with the teeth of the pivoted jaw, an operating rod yieldably connected with the insert and slidably supported on the shank, and means on the rod and 95 cooperating with the said shank for limiting the movement of the rod.

7. The combination with the shank and fixed toothed jaw of a wrench, the shank having a guide thereon, of a rod slideable in 100 the guide and having stop means for engagement with the guide, a tapered member pivotally connected with one end of the rod, means between the rod and tapered member for normally urging the latter toward 105 the shank, said tapered member having teeth for interlocking engagement with the toothed face of the fixed jaw, said tapered member being fulcrumed on the fixed jaw for rocking movement into and out of engagement with the fixed jaw.

In testimony whereof, I affix my signature:

EDWARD L. CONRAD.
